[57] ABSTRACT

A dry shaver has an oscillatable shear unit and a drive connected with the unit for oscillating it, the drive being composed of at least one body having a plurality of bi-laminar oscillatory elements of ferro-electric ceramic material which are electrically and mechanically connected in parallel.

DRY SHAVER CONSTRUCTION

BACKGROUND OF THE INVENTION

The present invention relates generally to dry shavers, and more particularly to an improved dry shaver construction with a novel drive for the oscillatory shear unit of the shaver.

Dry shavers are of course already known in a great variety of different types and constructions. Generally speaking, however, the shear system of dry shavers utilizes an upper shear section which is usually stationary and provided with slots or openings and is most frequently known as a shear foil or a similar element. Located beneath this upper section is a lower section provided with cutter blades or the like which is either oscillated or reciprocated linearly or is given rotary oscillatory movement, in the former case the movement being along its longitudinal axis and in the latter case the movement being about its longitudinal axis. The two sections are spring-biased against one another so that, as the cutting edges on the cutter blades or the like of the lower section move over the inner surface of the upper section or shear foil past the slots or openings therein, they will sever any hair which extends through them. Frequently such dry shavers are also provided with a trimming arrangement in form of two long rows of teeth provided on the upper and lower section respectively and cooperating with one another to trim longer hairs, for instance the hair at the temples, as opposed to the short beard stubble.

The dry shavers known from the prior art mostly are constructed with an electromagnetic oscillating armature and are intended to receive their electrical energy from a source of alternating current, usually being so constructed that they can be readily switched over for use either with a source supplying 110-125 volts or 220-250 volts. The armature oscillates with reference to an electromagnet which is fixedly mounted in the housing of the shaver and, together with one or more springs provided for this purpose, it constitutes a mechanical oscillator which oscillates at double the frequency of the alternating current source and which is connected with the lower section of the shear system by a swing arm as motion-transmitting element.

It is not surprising when it is pointed out that although this type of drive is relatively effective, it also is relatively bulky and heavy, particularly with reference to the overall weight of the other components of a conventional dry shaver. In addition the volume of sound generated by such a drive, and the vibrations resulting from its operation, are such as to be frequently found objectionable by the user.

SUMMARY OF THE INVENTION

It is, accordingly, a general object of the present invention to overcome the aforementioned disadvantages of the prior art.

More particularly it is an object of the present invention to provide an improved dry shaver construction which is not possessed of these disadvantages.

A concomitant object of the invention is to provide such a dry shaver construction which utilizes different principles than those known from the prior art for converting electrical energy into mechanical work.

Another object of the invention is to provide such a dry shaver construction in which the drive for the shear system is smaller, lighter in weight, quieter and pro-

vides fewer vibrations or vibrations of a less objectionable character than what is known from the art.

In pursuance of the above objects, and of others which will become apparent hereafter, one feature of the invention resides in a dry shaver which, briefly stated, comprises an oscillatable shear unit and drive means connected in motion-transmitting relationship with the shear unit and including at least one body which comprises a plurality of bi-laminar oscillatory elements of ferro-electric ceramic material connected electrically and mechanically in parallel with one another.

The novel drive according to the present invention is based upon a utilization of the reverse piezo effect known as electrostriction to those skilled in the art. There are now available ferro-electric ceramic materials such as barium titanate, lead zirconate titanate and the like, which permit—having with respect to conventional or classical piezo crystals a need for an excitation current which is lower by two decimal powers than in such conventional crystals—the construction of oscillatory motors of small output but usable effectiveness. It is of particular advantage that in constructions using such materials the mechanical fundamental frequency can be coordinated with the frequency of the alternating current with which the motor is supplied.

It is already known to produce from ferro-electric ceramic materials so-called flexible oscillators by fixedly connecting two thin electrode-carrying ceramic strips with one another and to fix them at one side or at two sides. Such elements are known as bi-laminar flexible oscillators and their mechanical resistance and permanent bending strength can be improved by incorporating between the ceramic strips an approximately equally thick metal strip which may also be constructed as a coupling element, depending on the use to which the respective element is to be put. It is a characteristic of these bi-laminar flexible oscillating elements, hereafter for the sake of convenience identified as "oscillating elements", that they are electrically polarized in the direction of their thickness. This means that the frequency of the excited mechanical oscillation is that of the excitation current applied to the electrodes, not double as is the case in electromagnetic oscillatory armature motors or magnetostrictive oscillators.

However, it has been found that oscillating elements of the type here under discussion cannot be used per se as oscillating drives for the movable components of a dry shaver shear unit. The reason is that the usable mechanical output of these oscillating elements is very small because of the very low mechanical resonance frequency mentioned above. The invention overcomes this problem by connecting several of the oscillating elements in such a manner that the summation of the outputs of the elements provides the required characteristics and the elements together constitute the oscillatory body of a ferro-electric oscillatory drive or motor.

The drive according to the present invention can be constructed in various ways in accordance with different embodiments. It is possible to locate the bi-laminar oscillatory elements adjacent one another with their ends—that is their opposite ends—being fixed in respective mounting rails one of which is fixed in the housing of the dry shaver and the other of which is connected with the movable component or section of the shear unit via a suitable motion-transmitting element. This embodiment is suitable both for shear systems

with a linearly oscillating movable component and for shear systems with a movable component which is mounted for rotary oscillation. In the first instance the oscillatory members are arranged so that the major surfaces of adjacent ones face one another in juxtaposed relationship, and the oscillatory body oscillates in its own plane in parallelogram-like movements, and in the second instance the oscillating elements are arranged adjacent one another with their longitudinal edges facing and the oscillatory body constitutes an oscillatory surface which laterally oscillates out of its center or normal plane.

According to another embodiment the oscillating elements can be arranged adjacent one another with their opposite ends being held in a frame which in turn is mounted in the housing of the dry shaver, whereas their oscillating portions are connected with one another and coupled with the movable component of the shear system via a motion-transmitting element. Such a construction is particularly suitable for shear systems having a movable component which is mounted for rotary oscillations.

The construction according to the present invention, as will be appreciated, is highly simple in structure. Because of this it permits compensation of the movable masses in such a manner that the motor is subdivided for instance into two oscillating bodies whose individual oscillating elements are so polarized or electrically connected that the oscillating bodies will perform mutually opposite oscillatory movements when connected to alternating current. The oscillating bodies can be coupled jointly with a single movable component of the shear system, or they can each be coupled with such a movable component with the movable components being located in known manner coaxially or laterally adjacent one another.

If the dry shaver utilizes a shear system or unit having two mutually linearly oscillatable movable components, then according to a further concept of the invention a single oscillating body can be utilized whose oscillating elements are connected at their opposite ends with respective rails which are fixed to them as already mentioned before. In this case, however, each rail is connected with one of the movable components, preferably via an articulate or flexible motion-transmitting element which serves for mounting the respective movable component. The individual oscillating elements are fixedly connected in this construction to rails at their opposite ends with their maximum deflection—that is oscillatory movement out of their normal rest position—taking place in their middle region. This means that the oscillating body as a whole performs contraction oscillations with double the frequency of the applied alternating current, which oscillations are directly transmitted to the movable components of the shear unit. In such a construction it may also be of advantage to employ the mass-compensation principle within the oscillatory motor itself in such a manner that the oscillating elements are electrically so connected—either for the entire motor or in two separate groups—in alternating relationship that when alternating current is applied to them they will perform mutually opposite oscillatory movements so that the mass center of the oscillatory motor remains at rest.

Oscillating motors of the type here under discussion will operate particularly effectively if not only the center metal strip of each oscillating element is fixedly

connected to mounting rails or the like, but also its ceramic strips. This assures a maximum possible oscillatory deflection as a result of the electrostrictive forces, also and particularly at the location where the connection is effected. It must be pointed out, however, that this advantage is ordinarily counteracted by the increased stresses acting upon the ceramic material with a concomitant danger or reduction of the permanent bending strength of this material. According to the invention this is avoided by providing a gradual transition

between the free length of the respective oscillating element and the location where it is fixedly secured. In a particularly advantageous manner from a point of view of manufacturing this is achieved by mounting the ends of the oscillating elements in their respective rails or other components by embedding them in castable resin. A further simplification can be achieved if the rails or analogous elements themselves are cast of castable resin in a form into which the ends of the oscillating elements are introduced so that they become embedded when the resin hardens.

Furthermore, the bending stresses at the locations where the oscillating elements are fixedly connected can be further removed in a substantial manner, if according to a particularly advantageous and preferred embodiment of the invention the polarization or excitation of the individual oscillating elements—which are connected at opposite ends with their respective mounting rails or the like in fixed manner—is selected in mutually opposite relationship for each half located at opposite side of the middle of the respective oscillating element. With such a construction the two halves of each oscillating element will, when being excited and operating, be deflected in mutually opposite directions so that the oscillatory configuration of the oscillating element during each oscillating movement will resemble the letter S, whereas the ends of the two halves at least approximately maintain the direction of their rest position. This construction has a better degree of effectiveness than the constructions utilizing deflection in only one direction.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1a shows in elevation a first embodiment of an oscillating element;

FIG. 1b is a partially sectioned side-elevation of the embodiment in FIG. 1a shown fixedly connected at one end;

FIG. 2a is a fragmentary view similar to FIG. 1a of an additional embodiment;

FIG. 2b is a partially sectioned side-elevation analogous to FIG. 1b but illustrating the embodiment of FIG. 2a in connected condition;

FIG. 3 is a fragmentary partly sectioned and partly broken away view of a dry shaver according to one embodiment of the invention;

FIG. 4 is a view analogous to FIG. 3 illustrating another embodiment of the invention;

FIG. 5a illustrates components of another embodiment of the invention;

FIG. 5b illustrates the embodiment with the components of FIG. 5a shown in position;

FIG. 6 is a fragmentary diagrammatic elevation of a further embodiment;

FIG. 7 is a fragmentary perspective detail view of another embodiment;

FIGS. 8a-8d illustrate diagrammatically an additional embodiment of the invention; and

FIG. 9 is a view analogous to FIG. 6 illustrating still a further embodiment of the invention.

DESCRIPTION OF THE PREFERRED EMBODIMENTS

Discussing now firstly the embodiment illustrated in FIGS. 1a and 1b it will be seen that we have there shown an oscillating element of bi-laminar construction and of already known type. A metallic strip or tongue 1 has secured at opposite sides to it thin strips 2 of a ferro-electric ceramic material on which metallic electrodes 3 are secured whose thickness is just sufficient to obtain the necessary conductivity. Soldered to the electrodes 3 adjacent the location where the element is fixedly secured, are connecting wires which are not illustrated because they are not believed necessary for an understanding of the invention and because it is desired to avoid making the illustration confusing.

The thickness of the member 1 and of the strips 2 is approximately equal and is selected between 0.1 and 0.3 mm. Preferably the choice is such that an individual oscillating element can be excited to an optimum extent by supplying between 110 and 125 volts alternating current. This means that if two of such elements are connected in series they require for their excitation 220 volts alternating current and a simple adjustment makes it thus possible to operate an oscillating motor constructed in this manner with voltages of 110-125 or 220-250 volts.

One end portion of the oscillating element is inserted into a recess of a mounting element, for instance a mounting rail 4, and retained as shown in FIG. 1b by being cast in place with a castable resin 5. The resin 5 provides for a fixed but not entirely inelastic connection which is thus protected against breakage due to the oscillation of the element. The castable resin tends to move up slightly along the electrode surfaces of the electrodes 3 above the point of connection, as indicated at 51, thereby in effect forming a support against kinking. At 11 the strip or tongue 1 projects slightly beyond the ceramic strips 2 and can there be connected for coupling with adjacent oscillating elements or with a component which is to have motion imparted to it, depending upon the circumstances of a particular application. The two ceramic strips are polarized in the direction of their thickness and their directions of polarization are so selected that they can be electrically operated in series.

When an alternating current is supplied to the electrodes 3, the oscillating element will oscillate in the same manner as a rod which is fixedly connected at one end; that is it will oscillate with its mechanical inherent or natural resonance frequency. The resonance depends upon the length and thickness of the ceramic strips essentially, and the characteristics of the materials used; advantageously it is so selected that the natural resonance frequency of the oscillating system will

be between 2 and 10, preferably between 3 and 5 Herz (Hz) above the operating frequency, that is normally above the net frequency of alternating current of 50 or 60 Hz or cycles. In known manner it can be precisely selected by changing the free length of the oscillating element.

In FIGS. 2a and 2b we have illustrated a further bi-laminar oscillating element whose opposite ends are fixedly connected in mounting rails 4, 4', respectively.

10 Here the electrode covers on the ceramic strips are interrupted in the region of the symmetry line a—a, so that each ceramic strip carries two electrodes 31 and 32. By exchanging the connections with the source of alternating current or by reversing the direction of polarization in the ceramic strips 2 on opposite sides of the symmetry line a—a, an S-shaped oscillatory deflection can be induced in the bi-laminar oscillating element 1, 2, with a point of reversal of direction in the region of the symmetry line a—a. It will be appreciated that the element in FIGS. 2a and 2b can also be considered—assuming that the electrodes extend over the entire length of the strips rather than being interrupted—as a construction whose largest oscillatory deflection occurs in the region of the center line a. In that case the strip 1 must be provided in this region with a laterally projection portion 12 as shown in FIG. 2b so that the element can be coupled either with other similar elements or with the component which is to have motion transmitted to it.

30 Coming now to FIG. 3 it will be seen that this illustrates in a highly simplified form a dry shaver having an apertured shear head. The housing is identified with reference numeral 21 and provided with a shear head frame 22 which can be disconnected from the housing and carries a cylindrically curved shear foil 23 which is sieve-like, that is apertured in the manner of a sieve or screen. Located beneath the foil 23, which is a stationary upper section or component of the shear unit, is a movable lower shear unit component 24 provided with cutting lamellas 241 of arcuate configuration; the component 24 is to be reciprocated or oscillated to and fro in the direction of the double headed arrow F and is lightly pressed by non-illustrated helical springs from below so that its cutting edges contact the underside of the shear foil 23. The component 24 is readily releasably coupled with a pin or projection 25.

35 The housing 21 further accommodates a ferro-electrical oscillatory motor 26 composed of a package of bi-laminar oscillating elements 1, 2, 3 of the type shown in either FIG. 1 or FIG. 2, which are mounted at opposite ends in two mounting rails 4, 4' with the major surfaces of adjacent ones of the elements 1, 2, 3 being juxtaposed. The lower rail 4 is fixedly mounted in the housing 21 whereas the upper rail 4' carries the coupling projection 25. The motor 26 oscillates at the net frequency, that is at the frequency of a current supplied to it. Reference numeral 27 identifies a socket in the bottom of the housing 21 so that via a suitable electrical cord the motor 26 can be connected with a source of alternating current.

40 In FIG. 4 we have illustrated an embodiment of the dry shaver in which the shear foil is identified with reference numeral 43, being held in a frame 42. Here, however, the component 24 is replaced by a substantially semi-cylindrical movable component 44 which is provided with elongated cutter lamellas 441 and which performs rotary oscillatory movements about an axis

442 journalled in the end faces of the frame 42, in the direction of the double-headed arrow G. A rib 443 is formed on the underside of the component 44, being of downwardly open U-shaped cross section.

The housing 41 in this case accommodates another ferro-electric oscillatory motor 46 composed of a packet of bi-laminar oscillating elements 1, 2, 3, this time of the type shown in FIG. 1 and arranged in a common plane with their lower end portions being mounted in a rail 4. The portions 11 of the oscillating element here engage into the hollow of the U-shaped rib 443 so that, when the motor performs oscillatory movements in the direction of the arrow H at the net frequency, that is the frequency of the source of alternating current, the component 44 will perform rotary oscillations about its axis 442.

In FIG. 5 we have illustrated a frame 471 having approximately the width of the movable component 44 and which is mounted in the housing 41' in parallelism with the base surface of the component 44. The frame 471 carries mounted at opposite ends a plurality of bi-laminar oscillating element 1, 2, 3 which oscillate in a common phase and whose center portion, where the maximum oscillatory deflection occurs, are connected via a comb-shaped member 48 which is provided at its upper side with one or more teeth 481. The member 48 in turn cooperates with a corresponding row of teeth 444 at the underside of the component 44. It will be appreciated that, as shown in FIG. 5a, two or several of such oscillating motors 47 can be arranged above one another and connected in parallel via their member 48, in order to obtain the necessary output. This embodiment is particularly suitable for producing a very low-profile apparatus whose housing 41' has an exterior configuration resembling a prism with strongly rounded edges as suggested in FIG. 5b and which can be readily gripped.

FIG. 6 is a diagrammatic illustration of the possibility of utilizing two or three mutually opposite oscillating movable components of the shear system, which are driven by an oscillating motor having a corresponding number of oscillating bodies. FIG. 6 shows a shear system having a U-shaped comb-like member 63 provided with slots 631 and two knife or blade-carrying members 64, and 64₂, which are also provided with slots 641. The members 64₁ and 64₂ are driven by oscillating bodies 26, and 26₂, respectively, of an oscillatory motor which is constructed in accordance with FIG. 3; reference numeral 25 designates the necessary coupling projections. The direction of oscillatory movement of the two bodies 26, and 26₂ during the two half waves of the net frequency is analogous to that indicated by the full-line and broken-line arrows, respectively which are shown in FIG. 8a. It should be pointed out that if a motor has two oscillatory bodies the switch-over from 110 to 220 volts can be effected also by parallel or series connection of the two oscillatory bodies.

The embodiment in FIG. 7 is somewhat analogous to that of FIG. 4 but has three turnably journalled movable components 44₁, 44₂, and 44₃ which are mounted coaxially on the shaft 442 and of which the outer ones, identified with reference numeral 44₁ and 44₃, together with their respectively associated oscillatory bodies 46₁ and 46₃, have approximately the same oscillatory mass as the middle component 44₂ with its associated oscillatory body 46₂. Because of this construction vibrations are completely compensated in this embodiment.

Coming now to FIG. 8 it will be seen that this illustrates a particularly advantageous embodiment of an oscillating motor for the drive of two movable components which oscillate linearly in mutually opposite directions at double the frequency of the motor. The two movable components are identified with reference numerals 74₁ and 74₂ and are swingably mounted above the base plate 7 of the non-illustrated housing with parallelogram linkages of articulated or springy rods 71, 10 with only the outer ones 71₁ and 71₂ being illustrated to avoid confusion. An oscillatory motor 76 is coupled with its mounting rails 4₁ and 4₂ with these outer rods 71₁ and 71₂, and the bi-laminar oscillating elements are connected at their opposite ends fixedly with the respective rails 4₁ and 4₂. The deflection of the oscillating element with the latter, or rather the direction of deflection, is of no consequence in this motor so that by appropriately choosing the polarity between adjacent oscillating elements, or between two adjacent groups of such elements, the oscillation can be made in mutually opposite directions so that the mass forces within the motor are compensated for as indicated in FIG. 8c.

It is advantageous to tune the oscillating system with at least one spring 77 tensioned between the articulated rods to resonance, unless the rods themselves are configured as springy rods and fixedly mounted in the base plate 7.

This particular embodiment has a further advantage, namely the fact that the oscillatory deflection of the motor 76 with respect to the height *a* of its coupling above the base plate 7 is transmitted in relationship to the length of the rods 71, and that this relationship can be selected as desired, so that the motor on the one hand and the shear system on the other hand can each be constructed for optimum advantage and be coordinated with one another.

It is also possible to modify the FIG. 8 embodiment by for instance replacing the component 74₂ with a shear foil 23 longitudinally slidably shiftably mounted 40 in a frame 22 such as shown in FIG. 1, as long as an appropriate mass compensation is provided. In this case the component 74₁ would extend over the entire length of the frame such as the component 24 in FIG. 1. In such a shear system both the foil and the cutter unit, that is the component 74₁, will oscillate with respect to the housing. It is possible in such a construction to make the amplitude of oscillations of the shear foil smaller and to keep it at a value such as has been found advantageous in accordance with test results in order 45 to be able to better guide the beard stubble into the holes of the shear foil than is possible with a stationary shear foil which is moved manually over the skin. It is also possible to modify FIG. 8 by providing the arrangement shown in FIG. 3, if the motor 76 is coupled with only one of the rods, for instance the rod 71₁, whereas 50 71₂ is a part of the housing 7 itself, namely a lateral wall thereof, as is suggested in FIG. 8d.

The embodiment in FIG. 9, finally, illustrates how an oscillating motor can be subdivided by providing it with two oscillating bodies 86₁ and 86₂, as is basically already disclosed in FIG. 6. This motor can drive a single movable component of the shear system, such as the component 24 of FIG. 3. Here, the packets of oscillating elements are connected at opposite ends again in mounting rails 4, 4' and are supported on a base plate 81 at different heights in order to be above —having them at identical length— to accommodate the trans-

mission member 83 which couples the body 86₂ with the connecting rod 82 provided on the body 86₁. The rod 82 in turn is coupled with the component 24 via the transmission member 25. The element 83 is a double-armed lever which is pivotable about the axis 84 and which serves for reversing the direction of movement of the output of the body 86₂ which oscillates in direction counter to the oscillation of the body 86₁. The axis or shaft 84 is journaled in a non-illustrated fork mounted on the plate 81.

With this embodiment vibrations can be effectively compensated despite the to and fro movement of component 24. The oppositely oscillating masses 24, 82, 86₁ on the one hand and 86₂ on the other hand, can be made identical by differential packet sizes of the two oscillating bodies and/or by mounting a compensating weight at the upper rail 4' of the oscillating body 86₂.

It will be appreciated that it is possible in this disclosure to suggest only some of the many possibilities for modifications which will offer themselves to those skilled in the art. Motors of the type here under discussion and disclosed, that is oscillatory motors based upon the use of bi-laminar oscillating elements of the type discussed, can be used in many applications, including the electrical drive of other small devices having a low power requirement besides dry shaves, and in which parts perform oscillatory or reciprocatory movements. This includes for instance devices used for hygienic and beauty purposes, such as electrical tooth-brushes, massaging brushes, vibrators, manicure devices and the like.

It will be understood that each of the elements described above, or two or more together, may also find a useful application in other types of constructions differing from the types described above.

While the invention has been illustrated and described as embodied in a dry shaver construction, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is:

1. In a dry shaver, in combination, an reciprocable shear unit; and drive means connected in motion-transmitting relationship with said shear unit, said drive means including at least one body which comprises a plurality of electrically connected bi-laminar oscillatory elements of ferro-electric ceramic material which are mechanically connected in parallelism with one another.

2. In a dry shaver as defined in claim 1; further comprising an articulated resilient transmission element connecting said drive means and shear unit in said motion-transmitting relationship.

3. In a dry shaver as defined in claim 1, said bi-laminar elements each having opposite ends and being arranged laterally adjacent to but spaced from one an-

other; further comprising a housing; and a pair of mounting rails each fast with said bi-laminar elements at one of said ends, one of said rails being mounted in said housing and the other being coupled with said shear unit.

4. In a dry shaver as defined in claim 3, said shear unit comprising an upper section and a reciprocating lower section; and wherein said drive means is connected with said lower section.

5. In a dry shaver as defined in claim 3, wherein said bi-laminar elements have major surfaces, and wherein the major surfaces of adjacent ones of said bi-laminar elements are juxtaposed.

6. In a dry shaver as defined in claim 3, said drive means comprising a cylindrically curved upper section and a lower section beneath said upper section and mounted for rotary oscillation about the cylinder axis of said upper section; and wherein said bi-laminar elements have respectively juxtaposed longitudinal edges and are arranged adjacent but spaced from one another.

7. In a dry shaver as defined in claim 6, wherein said bi-laminar elements are arranged in the plane of symmetry of said shear unit.

8. In a dry shaver as defined in claim 1, wherein said material is barium titanate.

9. In a dry shaver as defined in claim 1, wherein said material is lead-zirconate-titanate.

10. In a dry shaver as defined in claim 1; further comprising a housing and a frame mounted in said housing; wherein said bi-laminar elements are arranged adjacent but spaced from one another and have opposite ends fixed in said frame and oscillatory center portions, said drive means further comprising coupling means coupling said center portions for oscillations in unison; and motion-transmitting means connecting said center portions with said shear unit.

11. In a dry shaver as defined in claim 10, said shear unit having a cylindrically curved upper section, and a lower section mounted for rotary oscillatory movement about the cylinder axis of said upper section; and wherein said frame is mounted in parallel with said cylinder axis and extends normal to the center plane of said shear unit.

12. In dry shaver as defined in claim 1, said shear unit comprising a pair of shear sections, and said drive means comprising an additional body, each of said bodies being connected with one of said shear sections, and said bi-laminar elements of the respective bodies being connectable to alternating current and being polarized or electrically connected in such a manner that said bodies oscillate in mutually opposite direction.

13. In a dry shaver as defined in claim 1, said shear unit having two shear sections which are oscillatable in mutually opposite directions; said bi-laminar elements having opposite ends and being arranged adjacent but spaced from one another; and further comprising a pair of mounting rails each fixedly connected with said bi-laminar elements at one of said ends, each of said rails being coupled with a motion-transmitting member which engages a respective one of said sections.

14. In a dry shaver as defined in claim 1; further comprising at least one additional similar body; said bodies being connected with said shear unit and the bi-laminar elements of one of said bodies performing oscillatory movements oppositely to those of the other of said bodies.

15. In a dry shaver as defined in claim 1, said bi-laminar elements having a resonance frequency of their basic oscillation which is between 2 and 10 Hz higher than the frequency of a source of alternating current with which said drive means is to be connected.

16. In a dry shaver as defined in claim 15, wherein said resonance frequency is between 3 and 5 Hz higher than said frequency of said source.

17. In a dry shaver as defined in claim 3, wherein said bi-laminar elements each have two halves at opposite sides of a centerline intermediate their opposite ends, and wherein each half oscillates in direction opposite the other half so that during oscillation each bi-laminar element oscillates in a substantially S-shaped configuration.

18. In a dry shaver as defined in claim 3, said bi-laminar elements having opposite ends and outer laminae of ceramic material; and wherein said rails also engage said outer laminae at least at one of said opposite ends.

19. In a dry shaver as defined in claim 18, said rails being comb-shaped and slotted; and wherein said opposite ends are each received in one of said slots; and further comprising a hardenable resin in each slot retaining the respective end therein.

20. In a dry shaver as defined in claim 18, said rails being of synthetic plastic material, and said opposite ends each being embedded in one of said rails.
